UNITED STATES PATENT OFFICE.

JOSEPH LICHTENSTEIN AND ROBERT FLOCKE, OF NEWARK, NEW JERSEY,
ASSIGNORS TO R. NEUMANN & CO., OF SAME PLACE.

TRAVELING-BAG.

SPECIFICATION forming part of Letters Patent No. 363,654, dated May 24, 1887.

Application filed April 7, 1887. Serial No. 234,024. (No model.)

To all whom it may concern:

Be it known that we, JOSEPH LICHTENSTEIN and ROBERT FLOCKE, both citizens of the United States, both residing at Newark, in the county of Essex and State of New Jersey, have invented new and useful Improvements in Traveling Bags, of which the following is a specification.

This invention relates to improvements in traveling-bags, as set forth in the following specification and claims, and illustrated in the accompanying drawings, in which—

Figure 1 is a section in the plane xx , Fig. 2. Fig. 2 is a section in the plane yy , Fig. 1. Fig. 3 is a detail front elevation of part of a pair of frames. Fig. 4 is a section in the plane zz , Fig. 3.

Similar letters indicate corresponding parts.

In the drawings, the letters A B indicate the frames of a bag. C is a bottom bar having lugs or ears D. One of the frames—as, for example, the frame B—is rigidly or firmly secured to the lugs D of the bar C. The other frame is jointed or pivoted to the lugs D of the bar C, so that said frame can swing on the lugs.

In the drawings are shown pins or pivots E for jointing the frame A to the lugs D. As the frame B and the bar C are firmly united, the bar C partakes of the motion of the frame B when the frames A B are opened and closed.

To protect the material of the bag, the bar C has guards secured to such bar. The guards are made with two branches, F G. The branches F are secured to the bar C by suitable means, such as rivets H. The branches G rest alongside the frames and are secured to the frame B by suitable means, such as rivets I. As the guards F G are secured to the bar C, the guards move with the bar when the frames are opened and closed, and when the frames are opened the branches G of the guards are swung aside with the frame B and out of the way, so as not to interfere with the packing or unpacking of the bag.

In Fig. 2 sections K L of a bag are shown applied to the frames. A partition, M, is shown as being adapted to separate the sections K L. The partition M can be oscillated so as to cover 50 or uncover one section.

The partition M is provided with an axle or shaft, N. The bearings of the axle N are formed in lugs or ears O Q. The lug O is secured to one of the frames by suitable means, such as a rivet, P. The lug Q is held in place 55 by a movable arm or holding device, R. In the drawings the arm R is shown as being movable about a pivot, S.

By swinging or moving the arm R away from the lug Q said lug is free to be taken away 60 from the frame on which said lug Q is resting. The axle N can then be withdrawn from the lug O, and the partition M is thereby removed from the bag. By inserting a part of the axle N into the bearing or lug O, and by securing 65 the bearing or lug Q in place by the arm R, the axle N and partition M are secured in place. The partition M can thus be readily inserted into or removed from the bag.

What we claim as new, and desire to secure 70 by Letters Patent, is—

1. The combination of the bottom bar, C, the laterally-projecting lugs D, secured adjacent to the ends of the bar, the frame B, rigidly secured to the ends of the bar outside the 75 lugs and acting to turn said bar when the frame is swung open, and the frame A, attached by pivots E to the lugs at one side of the bottom bar, substantially as described.

2. The combination, with the frames A B, 80 of the bottom bar, C, rigidly secured at its ends to and turning with the frame B when the latter is swung to its opened and closed positions, and guards F G, secured to the bottom bar and the frame B and turning with said bar and 85 frame, substantially as described.

3. The combination, with the bag sections and frames, of a partition, M, having an axle, N, at its lower edge, a bearing, O, for one end of the axle, a removable bearing, Q, for the 90 other end of the axle, and a device for holding the removable bearing in place, substantially as described.

4. The combination, with the bag sections and the frames, of the partition M, having an 95 axle, N, at its lower edge, a fixed bearing, O, for one end of the axle, a removable bearing, Q, for the other end of the axle, and a pivoted swinging arm, R, for holding the removable bearing in place, substantially as described. 100

5. The combination, with the frames A B, of the bottom bar, C, rigidly secured at its ends to and turning with the frame B when the latter is swung open and closed, the laterally-projecting lugs D, secured to the bottom bar between the lower ends of the frames, and pivots E, attaching the frame A to the lugs at one side of the bottom bar, substantially as described.

In testimony whereof we have hereunto set our hands and seals in the presence of two subscribing witnesses.

JOSEPH LICHTENSTEIN. [L. S.]
ROBERT FLOCKE. [L. S.]
